DESIGN FOR A SIGNAL LIGHT FOR AUTOMOBILES

David Smith, Cleveland, Ohio

Application November 10, 1944, Serial No. 116,262

Term of patent 14 years

(Cl. D72—1)

To all whom it may concern:

Be it known that I, David Smith, a citizen of the United States of America, residing at Cleveland, in the county of Cuyahoga and State of Ohio, have invented a new, original, and ornamental Design for a Signal Light for Automobiles, of which the following is a specification, reference being had to the accompanying drawing, forming a part thereof.

In the drawing:

Figure 1 is a front elevational view of a signal light for automobiles embodying my new design.

Figure 2 is a top plan view of the same.

Figure 3 is an end elevational view of the same.

I claim:

The ornamental design for a signal light for automobiles, as shown.

DAVID SMITH.
